UNITED STATES PATENT OFFICE.

HENRY L. SCHWARZENBERG, OF CLEVELAND, OHIO.

DESIGN FOR AN ICE-SHREDDER.

SPECIFICATION forming part of Design No. 27,613, dated August 31, 1897.

Application filed June 26, 1897. Serial No. 642,548. Term of patent 31 years.

To all whom it may concern:

Be it known that I, HENRY L. SCHWARZENBERG, of Cleveland, Cuyahoga county, Ohio, have invented and produced a certain new and useful Design for Ice-Shredders, of which the following is a specification, reference being had to the accompanying drawings, illustrating the design.

In the accompanying drawings, Figure 1 is a top plan of the design. Fig. 2 is a side elevation of the same. Fig. 3 is a transverse section looking outwardly on about line III III, Fig. 2.

The ice-shredder comprises a circular or approximately circular plate A, that is provided centrally with a slot a, arranged transversely of the device. The forward side wall of said slot is turned downwardly and notched or serrated to form a row of teeth a'. The plate is provided with an upwardly-extending annular flange A', extending along the circular edge of the plate, and said flange at the

inner extremity of the plate terminates in a concavo-convex handle A², that extends upwardly and outwardly from the flange and has its convex side facing upwardly. Two reinforcing-ribs a² a³ are formed upon the device at the junction of the handle and flange, and said ribs diverge in the direction of the flange. The design consists, essentially, in the single piece of sheet metal stamped into the shape required to form the aforesaid members and the configuration and arrangement hereinbefore described.

What I claim is—

The design for an ice-shredder substantially as herein shown and described.

In testimony whereof I sign this specification, in the presence of two witnesses, this 17th day of June, 1897.

HENRY L. SCHWARZENBERG.
